[57] CLAIM

The ornamental design for a fishing harness for an inner tube, as shown and described.

DESCRIPTION

FIG. 1 is a perspective view of a fishing harness for an inner tube showing our new design;

FIG. 2 is a top view thereof;

FIG. 3 is a rear view thereof;

FIG. 4 is a front view thereof;

FIG. 5 is a right side view thereof, the left side being a mirror image; and,

FIG. 6 is a bottom view thereof.

The broken line showing of an inner tube in FIG. 1 is for illustrative purposes only and forms no part of the claimed design.

The broken lines on the claimed design in all views represent conventional top stitching.
